Primary Examiner — L. A. Grabenstetter(74) *Attorney, Agent, or Firm* — Birch, Stewart, Kolasch & Birch, LLP(57) **CLAIM**

The ornamental design for a monitor, as shown and described.

DESCRIPTION

1. Monitor
- 1.1 : Front Perspective view
- 1.2 : Rear Perspective view
- 1.3 : Front view
- 1.4 : Rear view
- 1.5 : Left side view
- 1.6 : Right side view
- 1.7 : Top view
- 1.8 : Bottom view
- 1.9 : Second Rear Perspective view, shown in a state of use
The broken lines indicate portions of the article that form no part of the claimed design. The broken lines in 1.9 depicting a power cable represent environmental subject matter which has been included to demonstrate a usage state for the monitor, and form no part of the claimed design.

1 Claim, 9 Drawing Sheets(56)
